PETER H. JACKSON, OF NEW YORK, N. Y.

Letters Patent No. 88,170, dated March 23, 1869.

IMPROVEMENT IN STEERING-APPARATUS.

The Schedule referred to in these Letters Patent and making part of the same.

To all whom it may concern:

Be it known that I, PETER H. JACKSON, of the city, county, and State of New York, have invented a new and useful Improvement in Steering-Apparatus for Vessels, of which the following is a full, clear, and exact description, reference being had to the accompanying drawing, forming part of this specification, and in which—

Figure 1 represents a partly sectional side elevation of my improved steering-apparatus, and

Figure 2, a plan of the same.

Similar letters of reference indicate corresponding parts.

This improvement has reference to that description of steering-apparatus in which a shaft, with a right-and-left screw-thread upon it, has been placed across the upper end of the rudder-head, and rotated by the steering-wheel, the motion being communicated to the rudder from nuts, fitting said screw-threads, and connected in a suitable manner with oppositely-arranged gudgeons on the rudder-head.

My invention consists—

First, in a novel arrangement of guide-rod to the nuts, or travelling screw-boxes, relatively to the double-screw shaft and rudder-head, whereby not only may a single guide-rod suffice to direct and keep from turning both nuts, but whereby a shorter screw, or main shaft and steering-apparatus, generally answer to produce a given motion to the rudder, than where separate guide-rods to the nuts, on opposite sides of the screw-shaft, are used, by reason of the arrangement of the guide-rod, which is over the double-screw shaft, admitting of a closer disposition of the rudder-head gudgeons to the axis of the rudder.

Secondly, the invention consists in a combination of the guide-rod to the nuts, with vertically-sliding bearings, or boxes to the double-screw shaft, whereby, while the rudder-stock is allowed to rise and fall by the working of the ship, or by the stern running aground, the whole is made to partake of the character of a permanent fixture, combining increased strength with freedom from derangement, the guide-rod and screw both uniting the vertically-sliding boxes with each other and with the nuts.

Referring to the accompanying drawing—

A represents the rudder-head, or upper portion of the rudder-stock, carrying oppositely-arranged vertical gudgeons, *a a*, which I prefer to fit, or surround with anti-friction rollers, *c c*, to render easier the working of the apparatus.

B is the main shaft, having right-and-left screw-threads, *d d*, on it, and being turned, or operated by a steering-wheel, C.

This shaft B has its bearings in and end-play restricted by boxes D D, fitted, or connected with the standards E E, in such manner as to be capable of sliding vertically, substantially as described in Letters

Patent of the United States, No. 77,288, issued to me, April 28, 1868, and which provides for the rudder-stock rising or falling by the working of the ship, or stern running aground, without straining or throwing friction on the screw, and keeping the latter in its proper position for working on the rudder.

F F are the nuts, or screw-boxes, arranged to fit the screw-threads *d d*, and provided with arms, *e e*, which have slots, *f f*, in them, within which the gudgeon-rollers *c c* play.

These nuts F F are directed and prevented from turning by a single guide-rod, G, arranged to lie parallel with and directly over the double-screw, or steering-shaft B.

By this disposition of the guide-rod G, not only does the one rod serve to guide both nuts F F, but such freedom of space is established on opposite sides of the shaft B, as that I am enabled to place the gudgeons *a a* much closer to the axial line of the rudder-stock than where separate side-guide rods to the two nuts are used, thereby diminishing the length of the screw and steering-apparatus generally, for a given stroke of rudder, which is a very important consideration, especially in the application of a screw steering-apparatus to a schooner or other small vessel, on account of the restricted distance there is between the rudder-stock and rail of the vessel.

Either nut F, it will be seen, passes the arm *e* of the adjacent nut, and in putting the rudder hard up or down, by turning the wheel C in reverse directions, the gudgeons *a a* may, by this arrangement, be worked almost close up to the double screw, or steering-shaft B.

Furthermore, this single guide-rod G is made to connect both vertical-sliding boxes D D, that are thus tied, and the nuts F F, with their slotted arms *e e*, carried by the screw and rod, thereby imparting great strength and stability to such working-devices, both in their general operation, and when rising and falling with the rudder-head, thus giving a permanency, or oneness of character, to the combination, and dispensing with objectionable joints.

What is here claimed, and desired to be secured by Letters Patent, is—

1. The combination, with the steering-screw shaft B and nuts F F, of the guide-rod G, arranged over said screw-shaft, and serving to guide both nuts, or screw-boxes, and prevent them from turning, substantially as specified.

2. The combination of the guide-rod G and vertically-sliding boxes D D, with the screw-shaft B and nuts F F, essentially as shown and described.

PETER H. JACKSON.
